UNITED STATES PATENT OFFICE.

FERDINAND BARRÉ, OF BALTIMORE, MARYLAND, ASSIGNOR TO ARMORED CONCRETE CONSTRUCTION COMPANY OF BALTIMORE CITY, A CORPORATION OF MARYLAND.

CONCRETE BEAM.

No. 865,963.

Specification of Letters Patent. Patented Sept. 10, 1907.

Application filed January 26, 1906. Serial No. 297,938.

To all whom it may concern:

Be it known that I, FERDINAND BARRÉ, a citizen of the United States, residing at Baltimore, in the State of Maryland, have invented new and useful Improvements in Reinforcements for Concrete Beams, of which the following is a specification.

This invention relates to improvements in reinforcements for concrete beams, such as shown and described in Letters Patent of the United States, dated 10 February 2, 1904, No. 751,427.

The object of the invention is to provide a cheap, simple, and efficient means for the reinforcement of beams constructed of concrete or other similar material.

Other features of the invention will be fully set forth 15 in the accompanying specification and pointed out in the claims.

In the accompanying drawings,—Figure 1 is a side elevation of a portion of a beam resting on one column and having one end projecting into the masonry or side 20 wall, the concrete being omitted. Fig. 2 is an inverted plan view of Fig. 1, the large lower rods being broken away. Fig. 3 is a vertical sectional view on the line $x-x$ of Fig. 1. Fig. 4 is a vertical sectional view on the line $y-y$ of Fig. 1. Figs. 5, 6, and 7 are detailed views 25 of one of the stirrups, showing the position of the bars that rest in the lower end and the bars that project through the upper end thereof.

Similar reference-numerals designate like parts throughout the several views of the drawings.

Referring to the accompanying drawings, forming 30 part of this specification, I designate the concrete beam, 2 the masonry or side wall, and 3 one of the columns. The stirrups 4 are formed of metal or other suitable material, the ends being first bent downwardly and 35 then upwardly, forming the bend 5 at the upper end, and the two bends 6 at the lower end, the extremities terminating on a plane with the upper bend 5. The bends 6 at the lower end are at right angles to the bend 5 at the upper end. The extremities and the upper 40 bend 5 of the stirrup 4 diverge to form a wide opening to the rods 7, 8 and 9 when they are being placed in the said stirrups. These stirrups 4 are placed along the beams in rows, in the present instance two rows, as seen in Figs. 2 and 3, at a suitable distance apart. The 45 straight rods 7 rest in the lower ends of the stirrups of each row and have one end projecting into the masonry and the other end resting over the column 3, or each end of the rod 7 may rest over a column. Two rods 8 and 9, which are somewhat smaller in diameter than the rod 50 7, rest in each row of the stirrups 4 above the rod 7 and one of said rods 8 has one end resting above the column 3 and the other end extending upwardly on an incline

at 10 and projecting into the masonry 2 near the top of the beam, and the other rod 9 in the same row of stirrups has one end projecting into the masonry 2 and the 55 opposite end extending upwardly on an incline at 11 and projecting over the column 3 near the top of the beam. There are always two rods 8 and 9 in each row of stirrups above the rod 7, one of said rods 8 projects upwardly at one end to near the top of the beam and terminates just beyond one of the columns and the other rod 9 in the same row of stirrups projects upwardly at the opposite end to near the top of the beam and terminates just beyond one of the columns, the upwardly-projecting ends of the rods 8 and 9 lie adjacent, and project beyond, each other over each column. The rods 12 project through the upper ends of the stirrups 4 at right angles to the rods 7, 8 and 9 and extend from one beam to another through the floor 13, as shown in Figs. 1, 2 and 3. After the stirrups 4 and rods 7, 8, 9 and 12, 70 12 are placed in position the concrete or other material is placed in position the concrete or other material is 75 filled in and the beam formed to any desired shape.

Having thus described my invention what I claim is:—

1. The combination with a beam formed of concrete or other suitable material, of two rows of stirrups 4, a straight rod 7 resting in the lower ends of the stirrups 4 of each row and projecting over two columns, and two rods 8 and 9 in each row of stirrups above the rod 7, one of said rods 8 projects upwardly at one end to near the top 80 of the beam and terminates just beyond one of the columns and the other rod 9 in the same row of stirrups projects upwardly at the opposite end to near the top of the beam and terminates just beyond one of the columns the upwardly-projecting end of the rods 8 and 9 lie adjacent, 85 and project beyond, each other over each column.

2. The combination with a beam formed of concrete or other suitable material, of two rows of stirrups 4 having their ends bent downwardly and then upwardly and terminating on a plane with the upper bend, forming four vertical rods, the bends at the lower ends being at right angles to the bend at the upper end, the upper bend and the extremities diverge to form a guide, a straight rod 7 resting in the lower ends of the stirrups of each row and projecting over two columns, two rods 8 and 9 resting in 90 each row of the stirrups above the rod 7, one of said rods 8 projects upwardly at one end to near the top of the beam and terminates just beyond one of the columns and the other rod 9 in the same row of stirrups projects upwardly at the opposite end to near the top of the beam and terminates just beyond one of the columns the upwardly-projecting ends of the rods 8 and 9 lie adjacent, and project beyond, each other over each column, and the rods 12 projecting through the upper ends of the stirrups at right angles to the rods 7, 8 and 9.

In testimony whereof I have signed my name to this specification in the presence of two subscribing witnesses.

FERDINAND BARRÉ.
